UNITED STATES PATENT OFFICE.

CHARLES W. CLARKE, OF CHARLESTON, WEST VIRGINIA.

RAIL AND ROAD-BED CONSTRUCTION.

1,076,190.

Specification of Letters Patent.

Patented Oct. 21, 1913.

Application filed February 4, 1913. Serial No. 746,155.

To all whom it may concern:

Be it known that I, CHARLES W. CLARKE, a citizen of the United States, residing at Charleston, in the county of Kanawha and

5 State of West Virginia, have invented certain new and useful Improvements in Rail and Road-Bed Construction; and I do hereby declare the following to be a full, clear, and exact description of the invention, such 10 as will enable other skilled in the art to which it appertains to make and use the same.

My invention relates to road bed construction for railways and more particularly to 15 the construction of the track rails thereof and it consists of certain novel features of construction and combination of parts as will be hereinafter clearly set forth in the following specifications and pointed out in 20 the claims.

The prime object of my invention, among others, is to provide what will be practically a continuous track rail for the tread of the wheels and which is so constricted as to be 25 rendered absolutely safe at all times, even though the track rail proper should become broken into a number of pieces.

A further object of my invention is to provide reliably efficient means whereby the 30 track rail proper is so mounted as to present a more or less yielding contact with the carrying wheels and thereby absorb to a maximum degree the pounding blows incident to the travel of the loaded train over the 35 same.

A further object of my invention, among others, is to so construct my carrying or track rail that it will be most reliably held in its adjusted position and whereby the securing bolts employed to unite the several 40 sections will be, at all times rendered conveniently accessible, as for the purpose of replacement or repair.

In illustrating the materialization of my 45 invention, attention is called to the accompanying drawings, in which,

Figure 1 shows a transverse section of my improved road-bed and trackway complete as applied to use. Fig. 2 is a side elevation 50 of my improved track rail, showing the usual form of tread. Fig. 3 is a plan view showing the preferred form or bracing means employed to hold the track rails in their relative positions. Fig. 4 is a detail 55 view showing the tread rail and web thereof provided with suitable bolt receiving aper-

ture designed to compensate for the relative movement between the tread and base members, and, Fig. 5 is a transverse sectional view of the tread rail and base therefor.

60

For convenience of description numerals will be employed, the same numeral being applied to the corresponding part throughout the several views, and referring to the numerals on the drawings, 1 indicates a portion of the road-bed which is preferably formed of concrete, though other kinds of material may be used, as preferred, and located or permanently embedded within the same, I dispose my base members 2, which I 70 have illustrated in cross section, and said base members it will be observed comprise a base section proper having upon its upper side a pair of parallel vertically disposed sections 3, properly spaced apart a sufficient distance to receive between them the web 4 of the tread rail 5.

75

It will be observed that the upper inner edges of each of the upright sections 3 are cut away or beveled so as to fit snugly 80 against the upwardly inclined faces 6 of the lower side of the tread rail, whereby said lower side will have a wedge-like fit between said beveled base, and it therefore follows that when the weight of the train, 85 or car, or cars, is placed thereon, the said upper members 3 will be caused to spread apart and incidentally lower the web 4 of the tread rail, it being understood that a suitable opening or space 7 is provided to 90 compensate for the lowering of said web. It will further be understood that any suitable cushioning material may be located in the space 7, if desired.

85

In Fig. 1, I have shown the tread rail as 95 being so formed as to be adapted for use in cities, where a minimum obstruction is to be presented in the street surface, while in Fig. 5, I have shown the tread 8 of that variety used upon steam roads, interurban lines, 100 and the like, it being understood that the tread may be made of any preferred kind to meet the requirements of the traffic and circumstances where the trackway is to be located.

105

In Fig. 1, I have illustrated how the road-bed proper may be made of concrete, or other permanent form of material, and at intervals immediately contiguous to the locking bolts 9 I have located suitable pockets or openings 10 in the concrete, which are designed to be filled with tar, bitumen, or 110

other suitable material which can be quickly removed when it is desired to gain access to the bolt heads or nuts thereon. It follows, therefore, that by providing these pockets or openings 10 filled with easily removed material, it is wholly unnecessary to disturb the permanent part of the road-bed in order to reach the locking bolts or nuts, as will be clearly obvious. It follows, therefore, from 5 the use of the construction of my improved permanent form of road-bed that should the tread rail become broken or should its removal for any reason become desirable, the locking bolts may be quickly reached and removed, when the tread rail may be lifted 10 bodily from its place and another substituted therefor, when the locking bolts are restored to their places and the openings which render them accessible are again filled, thus 15 leaving the surface of the street in its original perfect form or condition. The upper ends of the openings 10 are purposely left so shaped as to receive the locking caps 10^a and the wearing or tread plate 10^b, it being 20 understood that said parts are designed to rest upon suitable ledges or beveled shaped mouths of the holes 10, whereby they will be securely disposed in their adjusted position and may be quickly removed therefrom, as 25 desired. It follows therefore that by reason 30 of the base member 2 and its parallel spaced upright members 3, the tread rail proper may become broken into a number of pieces without endangering the safety of the train 35 passing over said broken parts, inasmuch as each part will be reliably held in its proper alinement to receive the tread of the wheel by reason of its peculiar relationship with the base member. It further follows that by 40 reason of the inclined faces 6 upon the lower 45 side of the tread rail, said tread rail will serve as a wedge-like member and will cause the upright sections or the guide flanges 3 to move outward away from each other when, by reason of their own resiliency, they will 50 be restored to their true vertical position when the load on the tread rail has been removed. The base members of the track rails proper are held in true and proper 55 alinement by reason of the Y member 11, it being understood that the bifurcated ends or branches 12 are so formed at their terminals as to each be provided with the upwardly curved terminal 13 which snugly fits over the outer edge of the base member, 60 while the other single end 14 of the Y member is similarly provided with the upwardly curved terminal 15, which snugly receives the outer edge of the other base member, 65 when by driving home the locking key 16 in its seat 17, the said base members are held against all relative movement inasmuch as the said Y members are alternately reversed when disposed in their operative positions.

In Fig. 5 I have shown the employment of a pair of spring washers 18 upon the locking bolt 9, which will permit a greater outward movement of each of the upright members 3 incident to the downward movement 70 of the tread rail when the load is passing over the same. I therefore reserve the right to use said bolts with or without the said spring washers or equivalent thereof, as I may find most desirable in practice. 75

It will therefore be clearly obvious from the foregoing specifications that by reason of the yielding movement which I have provided for the tread rail, when it is forced down between the guiding flanges 3 of the 80 base member 2, incident to the load passing over the same, I have very closely imitated or reproduced the result which is attained by the use of wooden ties, thereby imparting to the trackway that resiliency or cushioning effect which is to be found in practice 85 to be absolutely necessary to the preservation and prolongation, not only of the rolling stock, but also of the roadway itself.

It has been found in practice that if an 90 absolutely rigid form of road-bed and trackway are provided that the rolling stock as well, as the trackway itself, is soon destroyed. For such reason it has been found that concrete and metal ties embedded in 95 concrete, or other rigid road-bed, have proven a failure, whereas the old form of wooden tie has provided that necessary amount of resiliency which has insured success. Since, however, the wooden tie is 100 costly in maintenance and the life thereof is soon spent, it is my purpose to produce the same degree of resiliency as arises from the use of a wooden tie and at the same time to provide a form of great permanency and 105 reliability, and this result I have fully attained by providing a mounting for the tread rail, which shall be to a limited degree yielding in its character, as hereinbefore set forth. 110

By the use of the old form of wooden ties 115 the rails, as is well known, were spiked directly thereto, and were consequently held in proper alinement, and the requisite space or distance apart. In dispensing with the wooden tie, therefore, I wish to call particular attention to the importance of employing my form of Y-shaped brace or guide 11, hereinbefore described in detail, inasmuch as said bracing member will be found to be 120 reliably efficient in the performance of its office of truly alining the broken rails, or holding them locked in their true and accurate relationship. It will be obvious, therefore, that with the use of my improved rail 125 construction any kind of tie may be used, as for instance any of the solid metal or concrete ties, or as stated, my improved track rail will be found reliably efficient even though placed upon the solid rock, inasmuch 130

as it provides its own resiliency, which prevents its destruction incident to the pounding and jar which is so destructive to the present form of track rail.

5 While I have described the preferred construction and combination of parts deemed necessary in materializing my invention, I wish to include all substantial equivalents and substitutes as may fall fairly within the 10 scope of my invention.

It will be seen from the foregoing specifications that I have provided a permanent form of road-bed and trackway construction which will prove in operation to be practi-

15 cally indestructible and, should the track rail become worn or broken, it may be very quickly replaced without in any wise disturbing the traffic, inasmuch as all that is necessary to be done, after the locking bolts 20 have been removed, is to lift out the tread rail and drop in place the renewal thereof. It is believed that my improved form of 25 road-bed and track rail construction will greatly reduce the cost of maintenance of the road, thereby eliminating expensive labor and material charges.

What I claim and desire to secure by Letters-Patent is:

1. In a track-rail a base having a pair of 30 upwardly extending sections spaced apart and tapered at their upper edges, in combination with a tread rail having a web, and a wedge shaped section at the point of junction with the web whereby said wedge sec-

tion will fit between the upwardly directed 35 extensions of the base member, and suitable means to yieldingly hold said parts together.

2. In a cushioning track-rail, the combination with a base having a pair of upwardly directed members spaced apart; a tread rail 40 having a web to fit between said extensions on the base, a wedge-like section joining the web and tread sections together, whereby when the load is placed upon the tread rail the upwardly directed sections of the base 45 will be caused to move apart, and suitable means to hold a pair of track-rails in true alinement with each other.

3. A resilient or cushioning track-rail comprising a base having a pair of spaced 50 extensions upon its upper side, a tread rail having a web and a wedge-like section intermediate the tread and web, the said upwardly directed extensions being beveled on their inner side to fit normally against the 55 wedge section, whereby when the load is placed upon the tread rail the wedge section will be forced downward between the contacting edges of the extensions carried by the base. 60

In testimony whereof I have signed my name to this specification in the presence of two subscribing witnesses.

CHARLES W. CLARKE.
